UNITED STATES PATENT OFFICE.

FRANCIS WAYLAND, OF SALEM, MASSACHUSETTS.

SKIN, HIDE, AND LEATHER WORKING MACHINE.

1,214,852.

Specification of Letters Patent.

Patented Feb. 6, 1917.

Application filed May 18, 1912. Serial No. 628,094.

To all whom it may concern:

Be it known that I, FRANCIS WAYLAND, a citizen of the United States, and resident of Salem, in the county of Essex and State of Massachusetts, have invented new and useful Improvements in Skin, Hide, and Leather Working Machines, of which the following is a specification.

This invention relates to machine for stretching, staking, glazing and otherwise treating skins, hides and leather. The invention resides principally in the stretching belts, in the structural features thereof, and in the combination thereof with other elements of the machine, all as hereinafter more fully described and pointed out in the claims.

In the accompanying drawings which illustrate certain embodiments of the invention,—

Figure 1 is a side elevation of a leather working or treating machine embodying one form of the invention;

Fig. 2 is a sectional view through the upper part of Fig. 1, showing the relation between the rolls and one of the stretching belts, hereinafter described.

Fig. 3 is a fragmentary elevation, showing one arrangement of working projections for the working roll;

Fig. 4 is a side elevation of the stretching belts of Fig. 1, the work roll shown in broken lines;

Fig. 5 is a side view of a part of a leather treating machine embodying a modified form of the invention;

Fig. 6 illustrates in plan view the arrangement of the stretching belts of Fig. 5;

Fig. 7 is a fragmentary view in side elevation of the adjacent ends of two of said belts shown in Figs. 5 and 6;

Fig. 8 is a fragmentary face view of one of the stretching jaws shown in Fig. 5;

Fig. 9 is a fragmentary face view of the other of said stretching jaws;

Fig. 10 is a side elevation of a leather treating machine embodying still another modification of the invention;

Fig. 11 is a fragmentary view in elevation showing a part of one of the stretching belts of Fig. 10; and

Fig. 12 is a side elevation of a part of a machine similar to that of Fig. 10, also indicating laterally moving stretching and tension belts similar to those of Fig. 5 to

act upon the material before it passes to the vertically moving belts.

The frame of the machine on which all the parts are mounted is shown at 1. At either side of the frame 1 are the swinging arms 2, journaled to the frame at 3. The rolls 4 and 5 are pinch rolls or feed rolls which rotate in the direction of the arrows and draw the material M through the machine. The roll 4 is journaled on the frame 1 and the roll 5 is journaled on blocks 6, one at each side of the machine which slide in slideways on the arms 2, and are normally pressed in the direction of roll 4 by springs 7, to maintain a yielding pressure or pinch between rolls 4 and 5.

8 represents a bed roll journaled in frame 1 of the machine and 9 represents the work roll journaled in swinging arms 2. The work roll 9 is provided with leather working projections or vanes, which may be of any desired form, and as herein shown consist of diverging helical vanes 10, between which are arranged the knobs 11, suitable for glazing the leather. (See Figs. 1, 2 and 3.)

The mechanism for swing arms 2 to open position thereby separating rolls 4 and 5, and rolls 8 and 9, in order to introduce the skin or hide therebetween, is the same as that shown in Letters Patent of the United States, No. 1,131,756, granted me March 16, 1915, and need not here be further described; nor is it necessary to describe the detailed means for rotating the several rolls, which comprise the usual and well known operating devices in such machines, it being understood that the rolls severally rotate in the directions of the arrows.

Referring now to the stretching and tension belts shown in Figs. 1, 2 and 4, numeral 12 represents a bridge, U-shaped in cross section, extending across the machine from side to side and secured at its ends to the end uprights of the machine frame 1. The bridge 12 is adjustable upon the frame 1 by means of the adjusting screws 13, which are threaded into lugs 14 on frame 1. Four pairs of sprocket wheels 15, 16, 17 and 18, are journaled on the bridge 12, the sprocket wheels 15 and 16 carrying a pair of parallel sprocket chains 19, and the sprockets 17 and 18 carrying a similar pair of parallel sprocket chains 20. Each pair of parallel sprocket chains is connected by cross bars 21 secured to the chain at intervals, said cross

bars 21 being slightly curved or concaved to conform partially to the contour of the roll 9. A covering of leather or other suitable material 22 extends continuously 5 around the belt made up of the pair of connected sprocket chains, with its edges folded over and secured to the projecting ends of the cross bars 21, as best shown in Fig. 2. The two stretching belts thus formed, engage 10 the surface of work roll 9 and are caused to travel in opposite directions moving outwardly from their adjacent ends, toward the outer sides of the machine, in the direction of the arrows as shown in Fig. 4. The mechanism for causing the belts thus 15 to travel in opposite directions, consists of the shaft 23 rotated by a pulley 24 which is belted to a pulley on roll 8. Shaft 23 is provided with bevel gears 25 and 26 which engage 20 respectively bevel gears 27 and 28 on sprocket wheels 15 and 18, thereby rotating said sprocket wheels and driving said stretching belts.

In operation, the hide, skin or leather M 25 is held between work roll 9 and said pair of stretching belts, between work rolls 9 and bed roll 8, and between pinch rolls 4 and 5, as best shown in Fig. 2. The material M is drawn upward through the machine by said 30 pinch rolls and is acted upon by said work roll 9 and said oppositely traveling stretching belts, whereby the material is subjected not only to the effect of the projections on work roll 9 but also to the stretching and 35 spreading effect of said oppositely traveling belts, and thereafter is further subjected to the action of work roll 9 as the material passes between work roll 9 and bed roll 8. To support the stretching belt between the 40 sprocket wheels and maintain the necessary pressure thereof against the work roll 9, I provide a track 40 on bridge 12, made with a lengthwise groove into which project the tongues 41 of the cross bars 21. The cross 45 bars guided by said tongues slide along said track during the movement of the belts, and support the belt substantially throughout its whole extent between the sprocket wheels.

Referring now to the modification of the 50 invention shown in Figs. 5 to 9 inclusive: The work roll 9 may be the same as that heretofore described or it may be provided with any desired form of working projections, but instead of being journaled on the 55 swinging arms 2, is journaled on frame 1 of the machine. In this modification also the bed roll 8 is journaled on the swinging arms 2, and the feed roll 29, movably mounted in guide ways in the machine frame, co-operates 60 with the bed roll 8 to feed and draw the material through the machine. Stretching jaws 30 and 31, constructed as described in my aforesaid Letters Patent of the United States No. 1,131,756, granted me March 16, 65 1915, are mounted respectively on the frame

1 of the machine and the swinging arms 2, so that they will open and close to admit of the insertion of the material therebetween. Below the stretching jaws 30 and 31 are two pairs of oppositely moving stretching and 70 tension belts, one pair mounted on a bridge 32, U-shaped in cross section, which extends from side to side of the machine frame 1 and the other pair mounted on bridge 33, U-shaped in cross section, which extends from 75 side to side of the machine and is supported by the swinging arms 2.

It will be seen that the stretching jaw 30 and the bridge 32 are both carried by a single plate 34 which is vertically adjustable on the machine frame 1 by means of a slot and bolt connection as shown at 35 and 36 in Fig. 5. A spring 37 normally urges the plate 34 upward, and a rod 38, which may be actuated by a pedal (not shown) is provided to move the plate and the parts carried thereby downward, to vary the pressure between the side faces of the vanes on stretching jaws 30 and 31, and also between the side faces of the co-acting vanes on the stretching and 90 tension belts carried by the bridges 32 and 33, and hereinafter described. Said stretching jaw 31 and bridge 33 are also carried at each end by a single plate 39, which is rigidly and immovably fixed to swinging arm 2. 95 Each bridge 32 and 33 supports a pair of stretching belts, and each such belt consists of a pair of parallel sprocket chains 42, mounted on sprocket wheel 43, which are journaled on the bridge. The sprocket chains 42 of each pair are connected by cross bars 44, the working faces of which are provided with projections on vanes 45, preferably inclined or diagonal to the path of travel of the belt. The vanes of the belts on bridge 32 project between the vanes of the belts carried by bridge 33, and vice versa. 105

The stretching and tension belts of each pair, thus constructed, are caused to travel in opposite directions, moving from the center of the machine outward as indicated by the arrows in Fig. 6, while the opposed belts carried by bridge 32 and by bridge 33 respectively, also are driven in opposite directions, so that their co-acting faces, with the 110 interlocking vanes 45, move in the same direction. The belts are driven as thus described by shafts 46, connected through bevel gears with the sprocket wheels in the manner already described with respect to Figs. 1 and 115 2. Each cross bar 44 is provided with a tongue similar to that of cross bars 21 of Fig. 2, which tongues slide on tracks provided therefor on bridges 32 and 33, similar to the tracks already described with reference to Fig. 2, thereby supporting the belts throughout substantially their whole extent between the sprocket wheels, and maintaining the necessary pressure between the two sets of co-operating stretching belts. Motion 120 125 130

is communicated from shaft 46 of one pair of belts to shaft 46 of the other pair of belts, through gears 47 and 48, which are held in mesh by link 49, gear 47 being always in mesh with gear 50 as both are journaled on swinging arm 2, and gear 48 being held constantly in mesh with gear 51 by link 52. The two sets of belts will therefore travel continuously in unison notwithstanding their separation by the swinging of arms 2, which insures the proper registration of the vanes 45 when the two sets of belts are closed together with the material between them, by swinging the arms 2 to closed position.

15 The skin traveling upward through the machine passes first between the two sets of stretching belts by which the skin is stretched, softened and worked laterally or outwardly from the center, thence between 20 the stretching jaws 30 and 31, which perform their stretching, softening and other functions, and thence between the work roll 9 and bed roll 8.

Referring now to the modification shown 25 in Figs. 10 and 11, the two pinch rolls or feed rolls are shown at 4 and 5, carried respectively by the frame 1 and swinging arms 2 of the machine. Two co-acting vertically stretching, moving belts are provided, one 30 mounted on the frame 1 and one mounted on the swinging arms 2. Each belt consists of a pair of parallel sprocket chains 53 mounted on sprocket wheels 54, the sprocket wheels 54 carried by the arms 2 being in fixed 35 bearings and the sprocket wheels 54 carried by the frame 1 being mounted on a plate 55 which is adjustable on frame 1 by a slot and bolt connection as shown at 56 and 57. A spring 37 similar to that in Fig. 5, normally urges the plate 55 upward, while a rod 40 38 similar to that shown in Fig. 5, may be provided to draw the plate 55 downward and with it the stretching belt carried thereby.

Extending at intervals between each pair 45 of sprocket chains 53 are cross bars 58, the working faces of which are provided with inclined vanes 59, diverging from the center of the bar as shown in Fig. 11. The vanes 59 of one belt project between the vanes 59 50 of the other belt, and the two belts are driven in unison in opposite directions, whereby the opposed coöperating faces are moved in the same direction as indicated by the arrows in Fig. 10. Said belts are driven in 55 unison, notwithstanding their separation by the swinging of arms 2, in a manner similar to that already described, by means of intermediate gears 60 and 61. The skin is drawn upward through the machine by the pinch 60 rolls 4 and 5 and passes between the downwardly moving opposed faces of the two belts, by which it is stretched, spread, softened and worked out by the interlocking vanes 59 of the opposed belts. Each 65 belt is supported between its sprocket wheels

by tracks 62 against which the sprocket chains bear, thereby holding the belts in coöperative relationship throughout the whole extent of their working surfaces between the sprocket wheels. If it is desired 70 to increase the pressure between the co-acting vanes or blades 59, rod 38 may be pulled downward by a pedal or other suitable means, thereby moving the belt carried by the plate 55 downward, varying the space 75 between the co-acting sides of said vanes, and increasing the pressure or tension exerted on the material by the vanes.

In Fig. 12 I have illustrated in combination with the machine of Fig. 10, with the 80 vertically moving belts, a set of laterally moving stretching and tension belts 62 and 63, which may be of the same construction as the laterally moving stretching and tension belts more fully illustrated in Figs. 5, 85 6 and 7. These belts 62 and 63 stretch the material laterally and place it under tension, before it passes to the vertically acting belts, in a manner similar to the action of the corresponding belts in Fig. 5, for acting on 90 the material and placing it under tension before it passes to the vertically acting devices of Fig. 5.

I claim:

1. In a machine of the character described, a pair of stretching belts mounted end to end, and adapted to travel in opposite directions from their adjacent ends, an opposed element or elements between which and said stretching belts the material passes, 95 and means to support said belts between their ends against the pressure exerted by said opposed element or elements.

2. In a machine of the character described, a pair of stretching belts mounted 105 end to end, and adapted to travel in opposite directions from their adjacent ends, and an opposed element or elements between which and said stretching belts the material passes, said belts provided with 110 projections adapted to engage and act upon said material.

3. In a machine of the character described, a pair of stretching belts mounted end to end, adapted to travel in opposite directions from their adjacent ends, and an opposed element or elements between which and said stretching belts the material passes, 115 said belts provided with vanes inclined to the path of travel of said belts.

4. In a machine of the character described, a pair of stretching belts mounted end to end, adapted to travel in opposite directions from their adjacent ends, and an opposed element or elements provided with working projections, said opposed element or elements coöperating with said stretching belts to act upon the material passing between them.

5. In a machine of the character de-

scribed, a pair of stretching belts mounted end to end, adapted to travel in opposite directions from their adjacent ends, each belt comprising a pair of parallel sprocket 5 chains between which extend means for engaging and acting upon the material, sprocket wheels on which said chains are mounted, and means to support said chains between said sprocket wheels.

10 6. In a machine of the character described, a pair of stretching belts mounted end to end, adapted to travel in opposite directions from their adjacent ends, each belt comprising a pair of parallel sprocket chains 15 between which extend means for engaging and acting upon the material, sprocket wheels on which said chains are mounted, and tracks to support said chains between said sprockets.

20 7. In a machine of the character described, a pair of stretching belts mounted end to end, adapted to travel in opposite directions from their adjacent ends, each belt comprising a pair of parallel sprocket 25 chains, cross bars connecting said chains at intervals, means supported by said cross bars for engaging and acting upon the material, and sprocket wheels on which said chains are mounted.

30 8. In a machine of the character described, a pair of stretching belts mounted end to end, adapted to travel in opposite directions from their adjacent ends, each belt comprising a pair of parallel sprocket 35 chains, cross bars connecting said chains at intervals, means supported by said cross bars for engaging and acting upon the material, sprocket wheels on which said chains are mounted, and tracks on which said cross 40 bars slide to support said belts between said sprocket wheels.

9. In a machine of the character described, a pair of stretching belts mounted end to end adapted to travel in opposite 45 directions from their adjacent ends, and an opposed moving element or elements coöperating with said belts to act upon the material passing between said belts and said opposed moving element or elements.

50 10. In a machine of the character described, a pair of stretching belts mounted end to end, adapted to travel in opposite directions from their adjacent ends, and an opposed moving element or elements having 55 diverging inclined vanes, said opposed element or elements coöperating with said belts to stretch the material passing therebetween laterally in each direction.

60 11. In a machine of the character described, a work bed having working projections, and a pair of stretching belts pressed against the work bed mounted end to end, adapted to travel in opposite directions from their adjacent ends to stretch 65 the material passing between the work bed

and the belts laterally while the same is being acted upon by the work bed.

12. In a machine of the character described, a work bed having diverging vanes and a pair of stretching belts pressed 70 against the work bed mounted end to end, adapted to travel in opposite directions from their adjacent ends, the diverging vanes of said work bed and said belts coöperating to stretch the material passing therebetween 75 laterally in each direction.

13. In a machine of the character described, a stretching device comprising a yieldingly supported rear engaging element, a swinging frame, a front engaging element 80 carried by said swinging frame, said front-engaging element being composed of a pair of horizontally arranged endless belts movable in opposite directions, and a series of blades carried by said belts adapted to engage a hide when the frame is swung into engaging position, substantially as described.

14. In a machine of the character described, in combination, a hide backing member, a plurality of belts movable in opposite directions and carrying working edges which coöperate with the hide while supported by the backing member, a support for the said movable endless belts movable toward and from the said backing member, and feed rolls located above the endless belts and their backing member to draw the hide or skin up between the backing member and the endless belts when the latter are in their operative position.

15. In a machine of the character described, in combination, a backing member, endless belts provided with working edges coöperating with the backing member to spread the hide or skin laterally, pressure 105 members located above the spreading members and co-acting to squeeze the hide or skin passing between them, and means for drawing the hides or skins through said pressure members after they have been 110 passed between the spreading members.

16. A machine of the character described, comprising two coacting stretching belts provided with vanes, the vanes of one belt intermeshing with the vanes of the other belt, 115 and means to adjust said belts relatively one to the other in a plane parallel to the planes of travel of said belts to vary the side pressure exerted on the material between the coacting sides of said vanes.

17. A machine of the character described, comprising a stretching belt provided with vanes, an opposed element also provided with vanes projecting between the vanes of the belt, and means to adjust said belt and said opposed element relatively one to the other in a plane parallel to the plane of travel of said belt to vary the side pressure exerted on the material between the coacting sides of said vanes.

18. A machine of the character described, comprising, in combination, mechanism to stretch the material in a vertical direction, and mechanism moving laterally outward in each direction from the middle for stretching the material laterally before it passes to the first named stretching mechanism.
19. A machine of the character described, comprising, in combination, a pair of opposed vertically moving stretching belts,

and two pairs of opposed laterally moving stretching belts, adapted to stretch the material laterally before it passes to the vertically moving belts.

Signed by me at Boston, Massachusetts 15 this 14th day of May, 1912.

FRANCIS WAYLAND.
